UNITED STATES PATENT OFFICE.

JOSEPH F. RIVARD, OF DETROIT, MICHIGAN.

DESIGN FOR A REAR AND SIDE VIEW MIRROR FOR VEHICLES.

Application filed September 10, 1923. Serial No. 7,169. Term of patent 3½ years.

To all whom it may concern:

Be it known that I, JOSEPH F. RIVARD, a citizen of the United States, residing at Detroit, in the county of Wayne and State of Michigan, have invented a new, original, and ornamental Design for Rear and Side View Mirrors for Vehicles, of which the following is a specification, reference being had to the accompanying drawing, forming a part thereof.

Fig. 1 is a front elevation, Fig. 2 a plan

view and Fig. 3 a side elevation of a rear and side view mirror for vehicles, embodying my design.

I claim:

The ornamental design for a rear and side view mirror for vehicles as shown.

JOSEPH F. RIVARD.
